US0D1078556S

(12) **United States Design Patent** (10) **Patent No.:** **US D1,078,556 S**
(45) **Date of Patent:** **** Jun. 10, 2025**

(54) **WALKING AID ATTACHMENT**

(71) Applicant: **Henan Huanzhong Network Technology Co., Ltd.**, Zhengzhou (CN)

(72) Inventor: **Xutao Teng**, Ruzhou (CN)

(73) Assignee: **Henan Huanzhong Network Technology Co., Ltd.**, Zhengzhou (CN)

(**) Term: **15 Years**

(21) Appl. No.: **29/969,214**

(22) Filed: **Oct. 21, 2024**

(51) **LOC (15) Cl.** **12-12**

(52) **U.S. Cl.** **D12/133**
USPC .....

(57) **CLAIM**

The ornamental design for a walking aid attachment, as shown and described.

DESCRIPTION

FIG. 1 is a front perspective view of a walking aid attachment, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front view showing the walking aid attachment in a use state;

FIG. 10 is a rear view showing the walking aid attachment in a use state; and,

FIG. 11 is a bottom view showing the walking aid attachment in a use state.

The broken lines in the drawings illustrate the portions of the walking aid attachment, which form no part of the claimed design.

1 Claim, 11 Drawing Sheets
